(57) **CLAIM**

The ornamental design for a feminine products carrier, as shown and described.

DESCRIPTION

FIG. 1 shows an overhead perspective view of the feminine products carrier of the present invention in an open state.

FIG. 2 shows an overhead perspective view of the feminine products carrier of the present invention in a closed state.

FIG. 3 shows an overhead view of the feminine products carrier of the present invention in an open state.

FIG. 4 shows an underside view of the feminine products carrier of the present invention in an open state.

FIG. 5 shows an end view of the feminine products carrier of the present invention in an open state; and,

FIG. 6 shows a side view of the feminine products carrier of the present invention in an open state.

The broken lines shown in the drawings represent environmental effects or potential embodiments and do not form any part of the claimed design.
